UNITED STATES PATENT OFFICE.

LEON F. MEUNIER, OF CLEVELAND, OHIO, ASSIGNOR TO CHICAGO PNEUMATIC TOOL COMPANY, OF NEW YORK, N. Y., A CORPORATION OF NEW JERSEY.

THROTTLE-CONTROL DEVICE.

Application filed April 25, 1927. Serial No. 186,340.

This invention relates to fluid pressure operated tools and more particularly to manually operable devices for controlling the pressure fluid. The invention has direct application to reversing throttle devices of the sleeve type.

One object of the invention is to limit at will the extent of movement of the throttle mechanism. Another object is to prevent accidentally reverse operation of a fluid pressure tool. Other objects will be apparent from the detailed description which follows:

In order to illustrate the invention, one concrete embodiment thereof is shown in the accompanying drawings, in which:

Fig. 1 is a plan view of a throttle handle secured to a fluid pressure motor or tool, only a portion of the latter being shown;

Fig. 2 is a sectional view on the line 2—2 of Fig. 1;

Fig. 3 is a transverse sectional view substantially on the line 3—3 of Fig. 2;

Figs. 4 and 5 are plan views of a portion of Fig. 1 showing the sleeve which operates the throttle mechanism in different operative positions.

The invention is disclosed as embodied in a manual control or throttle handle indicated generally at A and adapted to be secured in any suitable manner as by a clamp or union nut 6 to the handle extension of a motor casing B which may form part of a fluid pressure operated tool, such as a pneumatic tool adapted for drilling, reaming, tapping and similar operations. Since the motor which is to be controlled may be of any suitable or desired type and forms no part of the present invention, a more complete showing and description thereof is omitted.

The control device or throttle handle is of the reversing type and comprises a hollow or tubular grip portion 7 serving as a conduit for the motive fluid which enters the same through the fitting 8 to which a supply conduit (not shown) is attached. Rotatably mounted upon a reduced portion of grip 7 is a throttle sleeve 9 which is arranged to move the tubular member 10 disposed within a bore of the handle casing and supported for rotary movement in a bushing 11. A screw 12 threaded into openings in sleeve 9 and member 10 and extending through a slot 7a in the grip casing, provides the connection between

sleeve 9 and member 10. Member 10 extends beyond grip casing 7 to engage a stem 13 on a throttle valve proper 14 rotatably mounted within a bushing 15 within motor casing B so that rotary motion imparted to throttle sleeve 9 is transmitted to the valve proper 14. In the present device sleeve 9 is rotatable in either direction from a central or neutral position, which may be indicated to the operator through the action of a stop locator ball 16 backed by a spring 17 and engaging a bore 9a in the sleeve. Ball 16 and its spring 17 may be enclosed in a tube 18 extending transversely of the bore of the handle device. The throttle sleeve is shown in neutral position in Figs. 1 and 2. Rotation of the sleeve to the right to the position shown in Fig. 5, admits motive fluid to motor casing B to operate the motor in a forward direction while rotation of sleeve 9 from the neutral position, shown in Figs. 1 and 2, to the left to the position shown in Fig. 4 reverses the motor.

In performing certain kinds of work with portable tools, such as reaming, it is not desirable to reverse the motor, but to operate it in one direction only. The present invention, accordingly, contemplates suitable means for limiting at will the movement of the throttle sleeve so that the motor cannot be reversed. To this end sleeve 9 is formed adjacent one end with an axially disposed undercut slot or recess 20 in which is slidably disposed a block or slide 21. The adjacent portion of the grip casing is formed with a recess 22 of suitable extent to receive a portion of slide 21 when the latter is moved so as to project beyond sleeve 9. The extent of recess 22 is such as to receive the projecting end of slide 21 when the throttle sleeve 9 is at or between its neutral and forward position (Figs. 1 and 5) and not to receive it when sleeve 9 is moved from neutral to reverse position (Fig. 4). It is, accordingly, apparent that when the operation of the motor is to be limited to one direction only, the operator will force slide 21 with his thumb outwardly into recess 22 which will enable the motor to be operated in the forward direction but will positively lock the throttle sleeve 9 from movement to reversing position. Frictional means are provided for retaining slide 21 in its adjusted position. Such means may take the form of one or more coil springs 23 dis-

posed in bores 24 in the under face of slide 21 and arranged to bear against the portion of the grip casing therebeneath.

While a preferred form of the invention is herein shown and described, it is to be understood that the invention is not limited to the detailed description thereof, but covers all changes, modifications and adaptations within the scope of the appended claims.

10 I claim as my invention:

1. The combination with a fluid pressure operated motor of manual control means for the motive fluid for operating the motor in reverse directions, and means operable at will 15 for confining said first named means to operating the motor in one direction only.

2. The combination with a fluid pressure tool of a handle therefor having throttle means for controlling the admission of motive fluid to operate the tool in reverse directions, and means including a movable stop for 20 confining the operation of the throttle means to control of the tool in one direction only.

3. The combination with a fluid pressure 25 tool of a handle therefor serving as a conduit for the motive fluid, throttle means on said handle for controlling the admission of motive fluid to operate the tool in reverse directions, manual means for actuating said throttle means comprising a rotatable sleeve, and 30 stop means including a movable member operable at will to limit the movement of said sleeve so as to confine the operation of said tool to one direction only.

35 4. The combination with a fluid pressure tool of a handle therefor serving as a conduit for the motive fluid, throttle means on said handle for controlling the admission of motive fluid to operate the tool in reverse 40 directions, manual means for actuating said throttle means comprising a rotatable sleeve, and cooperating means in said handle and on said sleeve arranged for preventing rotation of said sleeve to tool reversing position.

45 5. The combination with a fluid pressure tool of a handle therefor serving as a conduit for the motive fluid, throttle means on said handle for controlling the admission of motive fluid to operate the tool in reverse 50 directions, manual means for actuating said throttle means comprising a rotatable sleeve, and cooperating means on said handle and on said sleeve arranged for preventing rotation of said sleeve to tool reversing position including a slide forming a stop member.

55 6. The combination with a fluid pressure tool of a handle therefor serving as a conduit for the motive fluid, throttle means on said handle for controlling the admission of 60 motive fluid to operate the tool in reverse directions, manual means for actuating said throttle means comprising a rotatable sleeve, and stop means operable at will to limit the movement of said sleeve so as to confine the 65 operation of said tool to one direction only

comprising a slide on said sleeve cooperating with a recess in the adjacent portion of said handle.

7. The combination with a fluid pressure tool of a handle therefor serving as a conduit 70 for the motive fluid, throttle means on said handle for controlling the admission of motive fluid to operate the tool in reverse directions, manual means for actuating said throttle means comprising a rotatable sleeve, and 75 stop means operable at will to limit the movement of said sleeve so as to confine the operation of said tool to one direction only comprising a slide disposed in an undercut recess adjacent one end of said sleeve arranged to be projected into a cooperating slot or recess in said handle.

8. The combination with a fluid pressure tool of a handle therefor serving as a conduit for the motive fluid, throttle means on said 85 handle for controlling the admission of motive fluid to operate the tool in reverse directions, manual means for actuating said throttle means comprising a rotatable sleeve, and stop means operable at will to limit the movement of said sleeve so as to confine the operation of said tool to one direction only comprising a slide disposed in an undercut recess adjacent one end of said sleeve arranged to be projected into a cooperating slot or recess 90 in said handle and friction means for maintaining said slide in adjusted position.

9. The combination with a fluid pressure tool of a handle therefor serving as a conduit for the motive fluid, throttle means on said 100 handle for controlling the admission of motive fluid to operate the tool in reverse directions, manual means for actuating said throttle means comprising a rotatable sleeve, and stop means operable at will to limit the movement of said sleeve so as to confine the operation of said tool to one direction only comprising a slide disposed in an undercut recess adjacent one end of said sleeve arranged to be projected into a cooperating slot or recess 105 in said handle and friction means for maintaining said slide in adjusted position comprising a coiled spring fitting in a bore in the under side of said slide and engaging said sleeve.

110 10. A throttle handle for attachment to a fluid pressure tool to control the motor thereof, said handle having a sleeve rotatable in both directions from a neutral position to admit motive fluid for forward and reverse operations of the motor, and means on said handle for restricting at will rotation of said sleeve to one direction only from said neutral position.

115 11. A throttle handle for attachment to a fluid pressure tool to control the motor thereof, said handle having a sleeve rotatable in both directions from a neutral position to admit motive fluid for forward and reverse operations of the motor, and cooperating 120

125

means on said sleeve and handle for restricting at will rotation of said sleeve to one direction only from said neutral position including a stop member movable axially of said handle.

12. A throttle handle for attachment to a fluid pressure tool to control the motor thereof having a sleeve rotatable in both directions from a neutral position to admit motive fluid
10 for forward and reverse operations of the motor, and means on said handle for restricting at will rotation of said sleeve to one direction only from said neutral position comprising

ing a slide member on said sleeve arranged to be moved so as to project therebeyond and 15 means maintaining said member and said sleeve in frictional contact so that said member remains in adjusted position, the handle having a recess to receive the projecting end of said slide member when the latter is in 20 sleeve locking position.

Signed by me at Cleveland, in the county of Cuyahoga and State of Ohio, this 28 day of February, 1927.

LEON F. MEUNIER.
